OTHER PUBLICATIONS4S Advanced Wildlife Solutions "4S Block Elevator" <https://www.youtube.com/watch?v=aAx5Xkr8Hi8> Jul. 23, 2020 (Year: 2020).*Primary Examiner — Susan Moon Lee*(74) Attorney, Agent, or Firm* — Ralph E. Jocke; Walker & Jocke(57) **CLAIM**

I claim the ornamental design for an animal feed block elevator, as shown and described.

DESCRIPTION

FIG. 1 is a front top right perspective view of the animal feed block elevator showing my new design which is shown with the mounting collar in broken lines which form no part of the claim herein.

FIG. 2 is a front bottom right perspective view of the block elevator shown in FIG. 1.

FIG. 3 is a top view of the block elevator shown in FIG. 1.

FIG. 4 is a front view of the block elevator shown in FIG. 1.

FIG. 5 is a left side view of the block elevator shown in FIG. 1.

FIG. 6 is a right side view of the block elevator shown in FIG. 1.

FIG. 7 is a back view of the block elevator shown in FIG. 1.

FIG. 8 is a bottom view of the block elevator shown in FIG. 1; and,

FIG. 9 is a front top right perspective view of the block elevator shown in FIG. 1 with the removable pins of the block elevator shown disengaged.

The broken line showing of a mounting collar is for illustrative purposes only and forms no part of the design claim.
